George P. Regan, Sr., San Francisco, and William E. Regan, Burlingame, Calif., assignors to Regan Industries, Inc., Burlingame, Calif., a corporation of California

Filed Aug. 18, 1959, Ser. No. 834,543

1 Claim. (Cl. 95—76)

This invention relates generally to apparatus for transferring a light image to a photosensitive surface and more particularly to such apparatus by which curved printing plates can be printed with photographic images without distortion of register.

In the making of a commercial printing plate, the plate is first coated with a photosensitive resist material, exposed to a powerful light image (generally through a photographic negative), and then etched to remove unexposed portions of the metal surface to form an image in relief.

Procedures and apparatus satisfactory for flat plates are well known, but they are entirely unsuited for curved or semicylindrical plates such as handled by the apparatus of the present invention. Specifically the printing apparatus herein disclosed is adapted for use in the system for making curved printing plates disclosed in copending application Serial No. 834,037 filed August 17, 1959.

Generally, it is an object of the present invention to provide an apparatus and procedure for printing photographic images on curved printing plates, without distortion, and on a repetitive production basis.

Another object of the invention is to provide a machine for this purpose in which the plates may be printed in perfect register with photographic negatives, to provide printed plates of exceptional quality.

Another object of the invention is to provide such a machine which is relatively simple in construction and operation.

Other objects and advantages of the invention will be apparent from the following description and from the drawings in which:

Figure 1 is a perspective view of a printing machine embodying the invention, showing the light source in open position;

Figure 2 is a view in side elevation of the machine of Figure 1;

Figure 3 is a sectional view with the light source in closed position taken along the lines 3—3 of Figure 2;

Figure 4 is a schematic view showing the manifold means by which forces in suction are exerted about the periphery of the plate holder;

Figure 5 is a fragmentary view like Figure 1, showing the resilient pressure blanket removed from the face of the plate holder; and

Figure 6 is a view showing a detail of a preferred form of resilient blanket.

In general, the printing machine of the present invention employs a curved plate holder provided with means exerting forces in suction about its periphery. A flexible resilient blanket is adapted to overlay the plate holder in such manner that a curved printing plate can be positioned between the holder and the blanket along with a superposed photographic negative or other means forming a desired light image. The flexible blanket has a transparent portion to permit exposure of the plate to a light source, which preferably is concentrically arranged with respect to the plate holder.

2

Referring to the drawings, 10 indicates a base frame for a curved, semicylindrical plate holder 12. As best seen in Figure 5, the upper surface of the plate holder is recessed as at 14 to receive a curved printing plate 16 and negative 17. The outer periphery of the plate holder is constructed with a continuous groove 18 which is in communication with conduit means 20 secured to the inner periphery of the plate holder by means of a series of apertures 22. The base frame 10 supports a vacuum pump or other suitable source of suction 24 (Figures 1 and 2) and means to operate the pump, such as the electric motor 26. The pump 24 functions to exert forces in suction about the periphery of the plate holder 12 through the continuous groove 18. This is accomplished by exhaust of gas through the flexible conduit 28 and through the manifold 30 (Figure 4) which communicates with the conduit 20. Preferably the manifold has branches 32 to distribute the suction forces equally about the conduit 20. A separate branch 34 also communicates with the surface of the plate through an aperture 36, for a purpose to be later explained.

As best seen in Figures 1 and 5, a flexible resilient blanket 40 is adapted to overlay the plate holder 12. The blanket is secured at one edge to the plate holder, for example, as at 42 in Figure 3. The opposite or free edge of the blanket is preferably weighted (e. g. by the rod 43) so that in the position of Figure 1 the blanket will assume a relaxed position in concentric alignment with the plate 16. The blanket is also provided with a transparent insert 44 of flexible plastic or other suitable material. This insert is constructed to be in register with the plate 16 and to permit exposure of the plate to a light image.

During a printing operation, the suction exerted between the plate holder and the resilient blanket (through the groove 18 and aperture 36), assures that the negative will be held in a position of desired register with the curved plate. Referring to Figure 3, suction exerted in the conduit 20 exhausts the air from the space between the blanket and plate holder through the apertures 22. Eventually, edge portions 41 of the blanket 40 are sucked into the continuous groove 18 to effectively seal the blanket against the plate holder. To insure a perfect registry it is also desirable to exhaust the air in the space 45 about the periphery of the plate and negative. In the preferred embodiment illustrated, this is accomplished by the separate exhaust aperture 36 in cooperation with a plurality of waffle-like protuberances 48 provided on the interior of the blanket 40. As will be understood the protuberances 48 provide passages 50 therebetween permitting removal of substantially all the air surrounding the edges of the plate and negative. The net result is that the negative is pulled tightly about the curved plate with the elimination of creases or wrinkles which might otherwise provide misalignment or undesired distortion.

The printing is preferably accomplished by means of a curved light source 60 concentrically positioned with respect to the plate holder 12. As illustrated in Figures 1 and 2, the light source is mounted in a frame 62 pivotally mounted on the base frame 10 so as to be swingable from an open position to a desired concentric position adjacent the plate holder. The frame 62 provides means for suitably mounting both the light source and a curved concentrically arranged reflector 66 spaced above the light source. Proper alignment of the frame 62 is obtained by the fixed pivots 68 and the resilient supports 70, provided on the base frame 10. The construction just described has effect of concentrating light uniformly on the curved surface of the plate, thereby insuring a rapid even exposure of such surface.

The operation of the apparatus just described can be summarized as follows: The flexible blanket 40 is removed from the surface of the plate holder 12, as in Figure 5, and a coated curved printing plate 16 positioned within the recessed area 14 of the plate holder. The negative 17 is then placed above the curved plate in a desired position of registry, and the blanket 40 moved to overlay the plate and negative, as in Figures 1 and 2. The pump 24 is now energized to exert a vacuum on the manifold 30, causing suction to be exerted through the aperture 36 and the apertures 22 communicating with the continuous groove 18. As a result, the blanket 40 is sealed against the plate holder and free air exhausted from about the edges of the curved plate and negative to insure that the latter is tightly held against the plate 16 in a position of perfect registry. The light source 60 is now swung to a concentric position above the plate holder, making use of the handle or support 72. Upon energizing the light element for a desired interval, light of predetermined intensity is caused to penetrate the resilient blanket and the negative to expose the surface of the plate. Upon swinging the light source 60 to an inoperative position, and releasing the vacuum, the printed plate 16 can be removed for further processing.

To those skilled in the art to which this invention relates, many changes in construction and widely differing embodiments and applications of the invention will suggest themselves without departing from the spirit and scope

of the invention. For example, various arrangements of the suction conduits, other than those illustrated, can be employed with equal success. In addition, a moving rather than a fixed light element might be employed (axial or curved) without appreciably varying the principles of operation. Accordingly, it should be understood that the disclosures and description herein are purely illustrative and are not intended to be in any sense limiting.

We claim:

In an apparatus for exposing a curved printing plate to a distortion-free light image, a curved plate holder, a flexible resilient blanket adapted to overlay said plate holder, said resilient blanket including waffle-like protuberances and passages on the inner surface thereof, conduit means in said plate holder in communication with said passages, a source of suction being connected to said conduit means, said blanket having a transparent insert adapted to register with said plate, and a curved light source concentrically positioned with respect to said curved plate holder, whereby a photographic negative can be positively held between said blanket and plate in a position of perfect registry with said plate.
